CLAIM

The ornamental design for a combined ski and boot sling, as shown and described.

DESCRIPTION

FIG. 1 is a perspective of a combined ski and boot sling showing my new design;

FIG. 2 is a top plan view thereof;

FIG. 3 is a side elevation view thereof;

FIG. 4 is a side elevation view thereof;

FIG. 5 is a bottom plan view thereof;

FIG. 6 is a side view thereof; and,

FIG. 7 is an alternative embodiment identical to the design illustrated in FIG. 1, with the exception of the boot loop and associated strap, which are removed.
